R. I. D. NICOLL

TRANSMISSION SYSTEM

Filed Feb. 20, 1920

Inventor:
Robert I. D. Nicoll.
by *CR Soper* Atty.

UNITED STATES PATENT OFFICE.

ROBERT I. D. NICOLL, OF SUMMIT, NEW JERSEY, ASSIGNOR TO WESTERN ELECTRIC COMPANY, INCORPORATED, OF NEW YORK, N. Y., A CORPORATION OF NEW YORK.

TRANSMISSION SYSTEM.

Application filed February 20, 1920. Serial No. 360,232.

To all whom it may concern:

Be it known that I, ROBERT I. D. NICOLL, a citizen of the United States, residing at Summit, in the county of Union and State 5 of New Jersey, have invented certain new and useful Improvements in Transmission Systems, of which the following is a full, clear, concise, and exact description.

This invention relates to transmission 10 systems and more particularly to transmission systems employing means for signaling.

In telephonic transmission systems it has been the practice to employ repeaters or amplifiers for improving the efficiency of 15 the transmission between widely separated stations. In one system of this nature, a link circuit including the amplifying means, is used at a central office for interconnecting the terminals of the line circuits leading 20 to the distant stations to thereby include the repeater or amplifier in the communication channel established between the separated stations. The characteristics of the line circuits vary considerably and in order to insure 25 the proper operation of a telephone repeater of the usual type, it has been the practice to provide a network or artificial balancing transmission line for cooperative association with each line circuit when the 30 repeater is employed. It is also necessary to provide means in the link circuit cooperating 35 with the associated line circuits to control suitable signaling and switching means.

In one system of this nature, it has been 40 the practice to employ separate switching terminals and conductors connected to the line circuits and link circuits to associate the proper artificial lines with the amplifying means.

It is the object of this invention to provide 45 a simplified and improved system of this character in which the extra conductors and associated switching terminals heretofore required for the association of the artificial line are eliminated by obtaining one 50 signaling and two transmission paths from the three conductors.

In order to attain this object, in accordance 55 with a feature of the invention, repeating coils are introduced in the artificial transmission lines and the associated line circuits which coils are interconnected with the single line terminal so that one transmission circuit comprises two conductors and a

winding of one repeating coil, while another 55 transmission circuit comprises the other conductor, a winding of the other repeating coil and the simplex conductors of the former circuit. A signaling path is also simplex upon the latter circuit and comprises the 60 three conductors in parallel.

This and other features, not specifically mentioned above, will clearly appear from the following specification and accompanying drawing which shows a sufficient portion 65 of a telephone exchange system to properly illustrate the invention.

In the drawing, two line circuits A and C extending to distant stations (not shown) terminate in jacks 1 and 20 respectively; at 70 a central office. The line circuit A is provided with the usual line lamp 2, the line relay 6, and the cut-off relay 5, while the line circuit C is provided with a line lamp 22, a line relay 26 and a cut-off relay 25. Artificial 75 balancing lines of any usual and well-known type diagrammatically illustrated by the rectangles NA and NC are also provided for the line circuits A and C respectively. Repeating coils 3 and 4 are included between 80 the jack 1 and the conductors of line circuit A and of artificial line circuit NA respectively, while similar repeating coils 23 and 24 are included in a similar relation between the jack 20 and the line circuit C and the 85 artificial line circuit NC respectively. A link circuit B of any usual type equipped with any well-known telephone repeater organization, such as that disclosed in the United States patent to Toomey, No. 1,407,- 90 604 of February 21, 1922, is provided at the central office and terminates in plugs 10 and 19 for association with the jacks 1 and 20 respectively. The repeater organization is not shown in detail since it is unessential to the 95 proper understanding of the invention and is therefore diagrammatically represented by the rectangle R. Repeating coils 13 and 14 are introduced between the repeater R and the plug 10, while repeating coils 15 and 16 100 are included between the repeater R and the plug 19. Drops 11 and 17 are employed to provide the usual supervisory signals. Balancing resistances 7, 12, 18 and 27 are included in the various sleeve conductors to 105 properly adjust the resistances thereof.

It is thought that the invention may be more easily comprehended from the follow-

ing description of the operation of the system shown on the drawing.

Signaling current being received over the conductors of line A and flowing through the left-hand winding of line relay 6 operates said relay. Lamp 2 is thereby lighted and relay 6 locked over obvious circuits. The operator, upon observing the lighted condition of lamp 2, inserts plug 10 into jack 1, operating the cut-off relay 5 over a circuit extending from battery to the mid-point of the left-hand winding of repeating coil 14, and thence in parallel one path including the lower half of such winding, the resistance 12, the sleeve contacts of plug 10 and jack 1, the resistance 7, the lower half of the right-hand winding of repeating coil 4, and the winding of cut-off relay 5 to ground, while the other path extends through the upper half of the left-hand winding of repeating coil 14 to the mid-point of the left-hand winding of repeating coil 13, and thence in parallel through the upper and lower halves of such winding, the tip and ring contacts of plug 10 and jack 1, and the upper and lower halves of the right-hand winding of repeating coil 13 to the mid-point of such winding, and thence through the upper half of the right-hand winding of repeating coil 4 to the mid-point of such winding where it joins the first traced path. The balancing resistances 7 and 12 are included to insure that the parallel paths are of equal resistance. Relay 5, in operating, releases relay 6 disconnecting the left-hand winding thereof from the line conductors as well as extinguishing line lamp 2. The operator, upon ascertaining through the medium of a listening key (not shown) that a connection is desired with line circuit C inserts plug 19 into jack 20, thereby operating cut-off relay 25 to disconnect line relay 26 from the conductors of the line circuit C. The operating circuit for relay 25 may be traced from battery to the mid-point of the right-hand winding of repeating coil 15 and thence in parallel, one path extending through the upper half of such winding, the balancing resistance 18, the sleeve contacts of plug 19 and jack 20, the resistance 27, the lower half of the left-hand winding of repeating coil 24, and the winding of relay 25 to ground, while the other path extends through the lower half of the right-hand winding of the repeating coil 15 to the mid-point of the right-hand winding of repeating coil 16 and thence in parallel through the halves of such winding, the tip and ring contacts of plug 19 and jack 20 and the halves of the left-hand winding of repeating coil 23 to the mid-point of such winding, and thence through the upper half of the left-hand winding of repeating coil 24 to the mid-point of such winding where it joins the first traced path. Balancing re-

sistances 18 and 27 are adjusted to compensate for differences in the resistances of the parallel paths.

Thereupon, conversational channels are established between the widely separated stations connected with the line circuits A and C. As is the usual practice, the talking currents transmitted from the output circuit of the repeater R in each case divide, a portion being transmitted over the connected line circuit to the distant station and a substantially equal portion passing over the associated artificial line circuit. Thus the talking currents passing to line circuit A are induced through the repeating coil 13 into a closed circuit including the tip and ring contacts of plug 10 and jack 1 and the right-hand winding of repeating coil 3 and, by virtue of the latter-mentioned coil, are induced to the line circuit A. However, the talking currents, in passing to the artificial line NA, are induced by repeating coil 14 into a closed circuit which may be traced from the upper terminal of the left-hand winding of repeating coil 14, to the mid-point of the left-hand winding of repeating coil 13, and thence over parallel paths including the upper and lower halves of the left-hand winding of repeating coil 13, the tip and ring contacts of plug 10 and jack 1 and the upper and lower halves of the right-hand winding of repeating coil 3 to the mid-point of such winding, and thence through the right-hand winding of repeating coil 4 and resistance 7, the sleeve contacts of jack 1 and plug 10 and the resistance 12 to the lower terminal of the left-hand winding of repeating coil 14. In a similar manner, the talking currents in passing to the line circuit C traverse a path including the repeating coil 16, the tip and ring contacts of plug 19 and jack 20 and the repeating coil 23, while the similar currents in passing to artificial line NC traverse from repeating coil 15 to repeating coil 24, over a path including conductors of line C and link circuit B leading to the tip and ring contacts of the plug 19 and jack 20, such conductors being simplex by windings of repeating coils 16 and 23, and including the associated sleeve conductors connected to the sleeve contacts of such terminals.

Upon the cessation of the conversation, signaling current may be impressed upon the line circuits at the distant stations in the ordinary manner, causing the operation of the drops 11 and 17 to provide disconnect signals whereupon the operator withdraws the plugs 10 and 19 from the jacks 1 and 20 respectively and all apparatus restored to normal.

Thus it will be evident that the conductors leading to the tip, ring and sleeve contact of the plug and jack when interconnected, are utilized to provide two circuits for talk-

ing current and one circuit for signaling current.

What is claimed is:

1. In a transmission system, three conductors interconnecting two points, repeating coils associated with two of the conductors at each point to form a series circuit for talking currents, another repeating coil at each point associated with the other conductor and connected to the mid-point of a winding of the first-mentioned repeating coil thereat to form another circuit for talking currents and a circuit for signaling currents connected to the mid-points of the 15 windings of said other repeating coils.
2. In a telephone transmission system, a plurality of line circuits, artificial balancing line circuits therefor, a common three contact terminal for each line and its associated 20 artificial line, a telephone repeating link circuit for interconnecting the lines and terminating at each end in three conductors, and cooperating means included in the link and line circuits to provide two circuits for talking currents and one circuit for signaling currents.
3. In a signaling system, a plurality of line circuits, artificial balancing line circuits therefor, a common three-contact terminal 30 for each line and its associated artificial line, a telephone repeating link circuit for interconnecting the lines and terminating at each end in three conductors, and cooperating means included in the link and line circuits to provide two circuits for talking currents.
4. In combination, a signaling line, a repeater therefor, a balancing network for said line, and a simplex circuit connecting 40 said network to said repeater.
5. In combination, a signaling line, a repeater, an artificial line and a three-terminal plug and a cooperating three terminal jack for connecting said repeater both to said 45 artificial line and said signaling line, one of said three-terminal devices being normally connected to said lines, the other of said three-terminal devices being normally connected to said repeater.
6. In combination, a signaling line, a bal-
- ancing network for said line, a repeater and a three-wire link circuit for connecting said repeater both to said line and said network, said repeater being connected to one of the other-mentioned devices by two of said wires 55 in parallel, the electrical path being completed by the third wire, said repeater being connected to the remaining device by said two wires acting in series.
7. In combination, a signaling line, a balancing network therefor, a repeater, a link circuit between said line and said repeater comprising two impedances, a connection between intermediate points of said impedances including a plurality of other impedances, means for associating one of said last mentioned impedances with said balancing network and means for associating one of said last mentioned impedances with 60 said repeater.
8. In combination, two transformers, connections between the terminals of the secondary winding of one of said transformers and the terminals of the primary winding of the other of said transformers, a connection 65 between the midpoint of said secondary winding and the midpoint of said primary winding, said last connection including windings of a plurality of other transformers, and a resistance in said third connection 70 having a value depending upon the direct current resistance of the winding of one of said transformers.
9. In combination, two transformers, connections between the terminals of the secondary winding of one of said transformers and the primary winding of another of said 75 transformers, a connection including a transformer winding between the midpoint of the secondary winding of the first transformer and the primary winding of the second transformer, and a source of signaling currents connected to the midpoint of the transformer winding in said third connection.

In witness whereof, I hereunto subscribe my name this 13th day of February, A. D. 1920.

ROBERT I. D. NICOLL.
